TO CONTINENTAL MOTORS CORPORATION, OF DETROIT, MICHIGAN, A CORPORATION
OF VIRGINIA.

CRANK-SHAFT.

1,228,350.

Specification of Letters Patent. Patented Jan. 20, 1920.

Application filed June 28, 1918. Serial No. 106,382.

To all whom it may concern:

Be it known that I, ROBERT A. WEINHARDT, a citizen of the United States of America, residing at Chicago, in the county 5 of Cook and State of Illinois, have invented certain new and useful Improvements in Crank-Shafts, of which the following is a specification, reference being had therein to the accompanying drawings.

- 10 This invention relates to counterbalanced crank shafts for multi-cylinder explosive engines and to an arrangement thereof whereby the running parts are held in balance, as near as may be, when in rotation, 15 by means so located in relation to the bearings of the shaft that torque between the bearings is obviated to a great extent and there is little tendency of the shaft to weave when turning at high speed.
- 20 The invention consists in the matters hereinafter set forth, and more particularly pointed out in the appended claims.

In the drawings,

Figure 1 is a view of a crank shaft of a 25 multi-cylinder explosive engine, counterbalanced and arranged to embody features of the invention;

Figs. 2, 3, 4, 5 and 6 are views in detail taken on the section lines II, III, IV, V, and 30 VI, showing the method and disposition of the counterbalance weight for the several portions of the shaft.

As herein indicated shown as one form 35 of the invention, a crank shaft for a six cylinder engine, has end journals 1 and 2 and intermediate journals 3 with single throw cranks 4 adjacent the journals 1 and 2, intermediate short cranks 5 and 6 adjacent the intermediate journals 3, double 40 throw crank arms 7 and 8 connected by wrist pins to the cranks 5 and 6, and other double throw arms 9 and 10, connected similarly to the cranks 4. In order to maintain the running balance of the parts 4, 7, 8, 9 45 and 10, counterbalance weights 11 and 12 are secured to the shaft adjacent the journals 1 and 2 at such angles, in relation to the parts as to provide substantially complete running balance to them and to the 50 wrist pins. Similarly counterbalance weights 13 on each side of the intermediate journal 3 balance the parts 5 and 6 to which they are directly opposite.

As a result of this construction, the parts 55 which lie adjacent to and between the two

outer and the middle journals are provided with counterbalances at such relation to the journals as to minimize all torsional effects and thereby prevent weaving of the shaft, as well as distribute the counterbalance 60 along the shaft adjacent the supported parts and bearings.

Obviously, changes in the details of construction may be made without departing from the spirit of my invention and I do 65 not care to limit myself to any particular form or arrangement of parts.

What I claim is—

1. In an explosive engine, a counterbalanced crank shaft having a plurality of 70 journals with single and double throw cranks between them, and counterbalance weights secured to the shaft adjacent the journal portions, counterbalance weights between any two pair of journals being adapted 75 to maintain a balance with the crank arms and wrist pin connections between said journals, and certain of the weights being disposed in angular relation to the companion cranks.

2. In an explosive engine, a counterbalanced crank shaft having a plurality of journals with both single and double throw crank arms between the several pairs of journals and counterbalance weights each 85 secured to the crank shaft adjacent the journal, certain of said weights being disposed in angular relation to the companion crank arms and others being radially disposed to their companion crank arms and said 90 weights being distributed so that the pair of weights between each pair of journals compensate for the crank arms between said journals when the shaft is running and maintain a substantially complete balance 95 thereof.

3. A crank shaft for a six-cylinder explosive engine comprising outer journal portions and an intermediate journal portion with single and double throw crank arms 100 between each outer journal and the intermediate journal, and counterbalance weights each secured to the shaft adjacent a journal, each pair of counterbalance weights between each outer and the intermediate journal portions maintaining a substantially 105 complete balance for the crank arms lying between said journal portions, certain of the counterbalance weights being secured in angular relation to the crank arms which they

balance and others being radially opposite their companion crank arms.

4. In a crank shaft having journal portions disposed at intervals connected by single and double throw crank arms, counterbalance weights secured in angular relation to the several crank arms at points adjacent to the several journal portions, the pair of counterbalance weights between each pair of journals being adapted to maintain a substantially perfect balance with the crank arms between said journals.

5. A crank shaft having a plurality of crank pins with radial arms and having

bearing portions at the ends of the crank 15 shaft, a counterbalance located adjacent each bearing portion, each of said counterweights having its longitudinal axis extending at an angle with respect to the longitudinal axis of the crank arm adjacent to it, each weight 20 counterbalancing the bending moment of the crank shaft when in running condition.

In testimony whereof I affix my signature in presence of two witnesses.

ROBERT A. WEINHARDT.
